DESIGN FOR A TEXTILE FABRIC OR SIMILAR ARTICLE

Frank Headon, Great Neck, N. Y.

Application January 4, 1941, Serial No. 97,818

Term of patent 3½ years

To all whom it may concern:

Be it known that I, Frank Headon, a subject of the King of England, residing in Great Neck, Long Island, county of Nassau, and State of New York, have invented a new, original, and ornamental Design for a Textile Fabric or Similar Article, of which the following is a specification, reference being had to the accompanying drawing, forming a part thereof.

The figure of the drawing is a plan view of a textile fabric or similar article showing my new design.

I claim:

The ornamental design for a textile fabric or similar article, as shown.

FRANK HEADON.
